UNITED STATES PATENT OFFICE

GEORGE W. COLE, OF ENCANTO, CALIFORNIA

SAND WASHER

Application filed June 26, 1928. Serial No. 288,371.

This invention relates to machines for separating sands from water in which they are carried.

It is an object of the invention to provide a washing machine in which a clean and dry separation of sands from water is effected by the rotation of a bucket-wheel about an inclined axis.

Another object of the invention is to provide a washing machine which simultaneously with the separation of the sand, removes leaves, sticks and other foreign matter from the water to prevent their being delivered with the sand, or of clogging the operating parts of the machine.

Dirt and mud carried in solution in the water are also removed, separate from the sands.

A further object of the invention resides in the provision of a sand washer which by means of a plurality of wheels in novel arrangement, separates the sands from the water in a plurality of different grades of fineness, thus making it possible to obtain in one and the same operation, sand for use in the production of concrete, so-called engine sand which is similar to concrete sand without the heavier constituents thereof, and plaster or mortar sand which necessarily must be finer than the other sands.

Another object is to provide means in a multiple machine of the above described character, in which sand of any desired fineness may be dehydrated either by itself or in addition to sands of different fineness, and still other objects reside in details of construction and arrangements of parts as will fully appear in the course of the following description.

The accompanying drawings show an embodiment of my invention,

Figure 1 representing a partially sectional front-elevation of a multiple washing machine designed to dewater sands in three distinct and different grades;

Figure 2, a section taken on the line 2—2 of Figure 1 and drawn to an enlarged scale, and

Figure 3, a section similar to Figure 2, showing a modified construction.

Similar reference characters designate corresponding parts throughout the views.

The material to be dewatered is fed from a launder 5 into a box 6 provided with a bottom outlet 7 for the discharge of water after the sands have been separated therefrom, and with an overflow for the separate removal of leaves, sticks and other foreign matter.

This overflow may be provided by a partition 8 that divides the interior of the box into two compartments 9 and 10, and the partition may be lower than the sides of the box, as shown in Figure 3, or it may have a series of openings 12 in a line parallel to and beneath the top of the box, as has been illus-

trated in Figure 2.

If the openings are used, the operation can

be regulated by closing any desired number

thereof by means of plugs 13.

The sand-separating element of the invention comprises a bucket- or shovel-wheel 14 adapted to bail the sand out of the material fed into the box and deliver in a substantially dry condition at a point of discharge outside the box. The wheel is mounted at the end of a shaft 15 that is mounted for rotation about an inclined axis in bearings 16 on a supporting frame 17 above the box.

The shaft is driven from a jack-shaft 18 by means of beveled gear-wheels 19 and 20, and a pulley 21 on the jack-shaft provides for its connection with a conveniently located source of power.

The bucket wheel at the end of the shaft overhangs a side of the box and dips into the box to within a short distance from the bottom of the same.

An apron 22 beneath the lower side of the wheel, prevents spilling of the loads of its buckets 23 while they are inside or above the box below the point of delivery.

In the multiple construction illustrated in Figure 1, three wheels as hereinbefore described, are mounted relative to one and the same box to rotate simultaneously about parallel axes by connection with one and the same line-shaft.

In the operation of the machine, the material is fed into the box at one end thereof by means of the launder 5, and the wheels

by their rotation separate the sands from the water and deliver them outside the box in three different grades as will hereinafter be further explained.

Should it be desired to obtain but one grade of sand or a plurality of grades less than the number of separating units in the machine, the launder may be moved to feed the material adjacent the second or third wheel as the case may be, and thereby eliminate the other wheels from the operation. The overflow holes corresponding with the idle wheels, through which foreign matter is removed, may be plugged at the same time as stated hereinbefore. Any suitable means, such as illustrated in Fig. 2 of the drawings, may be employed for shifting the launder longitudinally of the box to any desired extent.

Inasmuch as the sands settle in the box at rates corresponding with their different weights, the heavy sands that settle shortly after the material has entered the box ahead of the finer sands, are bailed out of the box by the first wheel adjacent the feed-point, separate from the lighter sands that are suspended in the water at higher elevations. The finer sands moving with the water toward the outlet of the box, fall in the path of the next following wheel which removes the lower stratum of the suspended sands which is of a finer grade than those removed by the first wheel, and the finest grade of sands that passed by the second wheel at a higher elevation settle in the path of the third wheel and are thus separately bailed out.

The three wheels deliver the loads of their buckets outside the box, in separate launders, bins or other receptacles not shown in the drawings.

It will be apparent that in the operation of the machine as herein described, the sands are delivered in a substantially dry condition owing to the slanting position of the wheels that causes the water to drain from the buckets while the solids are held in place by the apron.

All floating matter such as leaves and sticks are removed by the overflow. The sands delivered by the wheels are automatically separated in different degrees of fineness, or sand of any desired grade of fineness may be removed from the material by itself by adjustment of the feed-launder.

The capacity of the machine may be decreased or increased by varying the number of the separating units, to deliver any desired grades of sands, regardless of the amount of water fed into the box, and it will be seen that the machine dehydrates, classifies and cleans the sands in one operation.

It is to be understood that variations in the form, construction or arrangement of the various elements comprised in the machine, may be resorted to within the scope of

the invention as defined in the hereunto appended claims.

What I claim and desire to secure by Letters Patent is:

1. In a sand-washer, a box providing an unobstructed flow of material fed into the box at one end, to the other end of the same, a plurality of rotary bailing wheels mounted in successive order between the ends of the box, each of said wheels having peripheral buckets open in a face at right angles to its axis of rotation, and each wheel being slantingly disposed so that its said face overhangs a side of the box for the discharge of sand outside the same, an adjustable launder for feeding matter into the box, either at the feed end of the box, or in advance of any selected number of the wheels whereby to exclude the feed from the other wheels, and means for shifting said launder longitudinally of the box to any desired extent. 70

2. In a sand-washer a box having an overflow, a rotary bailing-wheel in the box having peripheral buckets in a face at right angles to its axis of rotation, the wheel being slantingly disposed so that its said face overhangs a side of the box for the discharge of sand outside the same, and means for regulating the capacity of the overflow. 80

3. In sand-washer, a box providing an unobstructed flow of material from one end to the other, a succession of rotary bailing wheels in the box, each having peripheral buckets open in a face at right angles to its axis of rotation, and each wheel being slantingly disposed so that its said face overhangs a side of the box for the discharge of sand outside the same, the box having an overflow for water adjacent each wheel, an adjustable launder for feeding material into the box either at an end thereof or in advance of any selected number of the wheels, whereby to exclude the feed from the other wheels, means for shifting the said launder longitudinally of the box to any desired extent, and means for obstructing any of the overflows exclusive of the others. 95

4. In a sand washer, a box having a vertical wall, a rotary bailing wheel having peripheral buckets open in a face at right angles to its axis of rotation, the wheel being slantingly disposed so that its said face overhangs the said vertical wall of the box for discharging sand outside the same, a bracket secured to said wall and provided at the inner face of the same with an inclined supporting portion, and an inclined apron secured to the supporting portion of said bracket and covering a portion of the face of the wheel to prevent the discharge of sand into the box and projecting over the top of the said vertical wall. 110

In testimony whereof I have affixed my signature.

GEORGE W. COLE.
